UNITED STATES PATENT OFFICE

164,146

FRAME FOR SUNGLASSES OR SIMILAR ARTICLES

James B. Wright, Philadelphia, Pa.

Application June 5, 1950, Serial No. 10,368

Term of patent 14 years

(Cl. D57—1)

To all whom it may concern:

Be it known that I, James B. Wright, a citizen of the United States of America, residing at Philadelphia, in the county of Philadelphia, and State of Pennsylvania, have invented a new, original, and ornamental Design for a Frame for Sunglasses or Similar Articles, of which the following is a specification, reference being had to the accompanying drawing, forming part thereof.

Figure 1 is a top plan view of a frame for sunglasses or similar articles, showing my new design;

Fig. 2 is a side elevational view thereof; and Fig. 3 is an inside view of one of the temples.

The essential features of my design reside in the part shown in full lines.

I claim:

The ornamental design for a frame for sunglasses or similar articles, as shown and described.

JAMES B. WRIGHT.
